UNITED STATES PATENT OFFICE.

EUGÉNE PAUL ALFRED VILLETTÉ, OF LILLE, FRANCE.

MEANS FOR STOPPING THE MOTION OF VESSELS.

No. 805,683.

Specification of Letters Patent.

Patented Nov. 28, 1905.

Application filed January 11, 1905. Serial No. 240,660.

To all whom it may concern:

Be it known that I, EUGÉNE PAUL ALFRED VILLETTÉ, engineer, of 2 Boulevard Bigo Danel, Lille, in the Republic of France, have 5 invented Improvements in Means for Stopping the Motion of Vessels, of which the following is a specification.

The present invention has for its object an arrangement of telescoping plates arranged 10 vertically and grouped together in sufficient numbers and level with the hull of the vessel below the water-line.

By way of example, this improved system is represented in the accompanying drawings, 15 in which—

Figure 1 is a plan of a vessel provided with this invention, the plates being shown as projected. Fig. 2 is a side view of the same. Fig. 3 is a view, on a larger scale, of two adjoining plates. Fig. 4 is a view, on the same scale and in section, of a telescopic plate when not in use—that is to say, flush with the hull. Fig. 20 5 is a view of the same plate, shown projecting to effect the stopping or manœuvring of 25 the vessel. Fig. 6 shows a plan of a modification of the preceding figures.

As shown in the figures, the plates are placed in groups *a* along the hull *b* of the vessel, Fig. 1. They are arranged alternately 30 or zigzag, so as to present a large resisting-surface to the fluid current formed by the speed of the vessel. The plates consist of two parts *c* and *d*, fitting and telescoping into each other, and they are arranged in the hull 35 *b* so that they project normally perpendicularly to the longitudinal axis of the vessel. The part *c* is held in the part *d* by means of projections *e* at the back, which abut against the interior shoulders *f*, formed by the hollow 40 part *d*. Stops *g* are made in the interior of the back end of the parts *d* in order to limit the movement of the flat plates *c* in the hollow parts *d*. These plates or parts *c* and *d* are arranged vertically in the hull *b* of the vessel, 45 so that they can slide with little friction, and for this purpose they are subject to a perfect amount of lubrication obtained as follows: A hole *l* is made in the casing *h* and brings the oil between the casing and the plate *d*, 50 whence it penetrates by a hole *m* above the plate *c*. When the plate *c* is brought out from the interior to the exterior, the oil is then driven through *m* and *n* to the bottom 55 of the casing, whence it is distributed under the plate *d* and that *c* by the passages or holes *o* and *p*.

Inside the vessel and behind each plate is fixed a tight metal casing *h*, which serves as a guide to the plates *c* and *d*. The bottom of this casing forms inside projections *i*, against which the plate *d* presses when at rest, Fig. 4. These projections have for their object to prevent too much adherence of the plate *d* against the bottom of the casing and also to allow the passage of the actuating agent—"compressed air"—which is introduced into the casing at the opening *k*, whence it penetrates behind the plate *c*, which is pushed out and draws with it by the hooks *e* the surrounding casing *d* against the shoulders *f*. The compressed air necessary for this operation is supplied by a special machine, the distributing valves or cocks of which are brought to a point conveniently accessible to the commanding officer or the officer of the watch. The 70 plates having produced their effect in stopping the vessel are brought back to their closed position by the opposite action to that used for driving them out—that is to say, by a vacuum made behind them in the casings *h*. 80

It is obvious that each group of the retarding-plates will have its special regulating-valve under the control of the officer in charge, so as to enable him to operate the whole or part of the apparatus whether for stopping 85 or manœuvring the vessel.

Fig. 6 shows in plan and in section a modification of the arrangement described above in which the retarding-plate *r* is made in the shape of a quarter of a circle and is jointed 90 to the hull *b*. Inside the hull this plate is contained in a tight casing *s* with an opening and pipe at *t* for introducing compressed air to force out the plate or for withdrawing the air to bring back the plate into *s*. 95

Having now particularly described and ascertained the nature of my said invention and in what manner the same is to be performed, I declare that what I claim is—

1. In apparatus for quickly stopping vessels in movement, plates consisting of two sections telescoping into each other when at rest and arranged vertically in zigzag form and in group along the length of the hull of the vessel: the inner section having projections and 100 the outer one stops to limit the movement of the interior one; and the outer plates having projections adapted to abut against the wall of the hull for the same purpose, substantially as described. 105

2. In apparatus for quickly stopping vessels in movement, plates consisting of two sec- 110

tions telescoping into each other when at rest and arranged vertically in zigzag form and in groups along the length of the hull of the vessel, the inner section having projections and 5 the outer one stops to limit the movement of the interior one, and the outer section having projections adapted to abut against the wall of the hull for the same purpose, in combination with a casing for each telescoping plate, 10 in which casing said plate is adapted to oper-

ate as described and means for admitting an operating fluid into and withdrawing it from the casing to effect the operation of the plate.

In testimony whereof I affix my signature in presence of two witnesses.

EUGÉNE PAUL ALFRED VILLETTÉ.
